(57) **CLAIM**

The ornamental design for an apparatus for lighting fires, as shown and described.

DESCRIPTION

FIG. 1 is a top, front, right side axonometric view of an apparatus for lighting fires in an opened configuration showing our new design.

FIG. 2 is a bottom, front, right side axonometric view thereof in a closed configuration.

FIG. 3 is a top, rear, right side axonometric view thereof in the closed configuration.

FIG. 4 is a right side elevational view thereof in the closed configuration.

FIG. 5 is a right side elevational view thereof in the opened configuration; and,

FIG. 6 is a front elevational view thereof in the opened configuration.
